SEMAUTOMATIC IGNITION CONTROL
DEVICE

Oswald Gaglio, Nice, France

Application September 29, 1950, Serial No. 187,543
In France September 30, 1949

8 Claims. (Cl. 123—117)

1

It is convenient to resort to the reduction in pressure in the gas intake of an internal combustion engine for controlling through a piston or a diaphragm a handle adjusting the timing of the ignition or a movable plate housed inside the "Delco" ignition means for adjusting same.

Such prior devices were actuated by the reduction in pressure provided by the suction exerted by the engine on the carburetter and their connection with the latter was located a few millimeters ahead of the throttle valve in its closed position. Consequently, at the beginning of acceleration when the throttle valve has executed $\frac{1}{5}$ of its stroke, the suction at the opening in the connection considered is at a maximum. In contradistinction, the remaining $\frac{4}{5}$ of the stroke do not even increase the suction but reduce it by three quarters as the engine picks up.

In other words, during a complete acceleration of the engine, the reduction in pressure in the connection is practically zero. Consequently the engines provided with a suction operated corrector for the timing of ignition will rattle under slow running conditions by reason of the exaggerated suction or else they are submitted to delay at high speeds as the reduction in pressure does not act any longer.

It is practically impossible to compensate the adjustment provided under such conditions by providing the piston or diaphragm with a regulator spring as if its action had for its result a lesser reduction in pressure at low speeds, and consequently a less advanced ignition, it cannot provide a more advanced ignition at high speeds.

My invention provides for a compound control of the ignition through the accelerator pedal and through the depression prevailing in the engine.

The acceleration of the engine corrects thus the action exerted by the main compensator spring, whereby the pressure exerted by said compensator spring is reduced by 75 to 100%. In other words, under certain rates of running, it is possible to slightly advance the ignition without resorting to the suction exerted by the engine. On the other hand and through the same arrangement, it is possible, under the action of the depression, to provide a curve of advanced ignition that is synchronous with the stress required from the engine. As a matter of fact, the synchronizing spring on which the engine exerts its suction is extremely sensitive.

According to my present invention, the operation of the arrangement may in a preferred embodiment include a piston, diaphragm or the

like equivalent member that is submitted to no elastic pressure beyond that due to the depression in the engine and the movements of said element are transmitted to the ignition timing means through an intermediary link that is held floatingly between two extreme positions by two antagonistic springs mounted between two stops carried by the end of the intermediary link on one hand and, on the other hand, a correcting lever through which said link passes. Furthermore said link and said lever correcting the stroke-limiting device are mounted inside a closed casing rigid with the casing of the make and break gear.

In accompanying drawing:

Fig. 1 is a diagrammatic view of a stabilizing device for the timing of the ignition according to my invention.

Figs. 2 and 3 show two modifications thereof.

Obviously, the embodiments illustrated by way of a mere exemplification may be modified within the scope of accompanying claims.

Turning to Fig. 1, the carburetter 2 provided with a throttle valve 3 is connected through the port 1 with a pipe 4 leading to the cylinder 5 inside which may move a piston 6; the latter is urged towards the bottom of said cylinder by a spring 7 submitted to an adjustable pressure by a screw 8 over which is screwed a locking counter nut 9. The head of the piston 6 is coupled through a link 10 with a lever 11 pivotally secured at 12 and connected through a connecting rod 13 with a disc 14 for correcting the timing of ignition, said disc 14 being keyed to the shaft 15 of the timing device 16 of the so-called Delco type.

To the end of the lever is pivotally secured a stop 17 acting through its bent end 18 on the counter nut forming the end of a strap 19 pivotally secured to the lever 11 through the rod 20 and a compensating spring 21 engaging freely a longitudinal slot 22 in said rod 20.

The strap 19 is also pivotally secured through a link 23 with the lever 24 controlling the throttle valve in the usual manner.

When the engine is started, there is no depression exerted through the port 1 during idling and the suction begins appearing when the accelerator has advanced by about $\frac{1}{5}$. The suction transmitted through the pipe 4 to the cylinder 5 acts on the piston 6 and when it has reached one fifth of its maximum value, it shifts the piston 6 against the action of the spring 7. The piston 6 acts through the agency of the lever 11 and of the connecting rods or links 10 and 13 on the

plate 14 providing for advanced ignition, said plate being driven in proportion with the rate of depression.

The piston 6 that is urged forwardly during its displacement is however stopped in its travel as the lever 11 carries along with it the stop 17 that is urged back by the strap 19 by reason of the pressure exerted on the latter by the spring of the control or accelerator pedal actuated by the driver.

By reason of the difference in lengths between the arms of the lever pivotally secured at 12, the stroke of the stop 17 is double that of the point of connection between the piston 6 and the link 10; as one fifth of the acceleration of the carburettor as provided by the throttle valve 3 corresponds to a travel by 5 mm. of the strap 19, the shifting of the lever 11 at the point of connection thereof with the piston is only equal to 2.5 mm.

In other words, the advance of ignition for one fifth of acceleration is only one half that that would be obtained without the stabilizing system disclosed. Any other fraction of acceleration depending on the ratio between the arms of the lever may also be contemplated.

The auxiliary compensating spring 21 that is drawn along by its rod 20 through the agency of an upper key and by the strap 19 is operative only beyond two fifths of the acceleration stroke. This provides compensation for the lack of depression exerted on the lever 11 controlling the plate 14.

In Figs. 2 and 3, the pipe 4 connected with the admission into the engine opens into the cylinder 5 inside which may move freely the piston 6; the head of said piston 6 is coupled as precedingly with the connecting rod controlling the disc 4 controlling the timing of ignition and keyed to the camshaft 15 of the timing device.

The connection between the head of the piston 6 and the link 13 is performed through the agency of an intermediary link 10 sliding freely inside an opening provided in the correcting lever 11 adapted to pivot round the point 12. The intermediary link 10 passes thus at a point of its length through the lever 11 against which bear, on either side thereof, two springs acting in opposite directions 26 and 7 engaging respectively the head of the piston 6 and a terminal stop 31 carried by the link 10 in the vicinity of the main link or connecting rod 13. It is thus apparent that the link 10 is floatingly mounted with reference to the lever 11 whereby it is possible for it to follow the movements of the piston 6 controlled by the suction applied to it and to oppose said movements to a slight extent.

The spring 26 forms thus a spring adapted to synchronise the advanced ignition; it is submitted to the low depression in the engine and exerts its action freely and accurately without being disturbed by the mechanical means controlled by the accelerator. On the other hand, the spring 7 forms a compensating spring submitted to the mechanical action of the lever 11 when the depression is too weak.

Furthermore, a connecting rod 23 controlled by the accelerator pedal acts, through the agency of the lever 33 pivotally secured to a stationary point, on a compensating rod 20 adapted to shift, through the agency of the springs 21 and 21', the correcting lever 11 through which said rod 20 passes. The spring 21 forming the main compensating spring provides for compensation of the total depression exerted by the engine while the spring 21' or accelerating spring pro-

vides for adjustment of the pressure exerted by the spring 21 on the compensating or correcting lever 11. Said lever 11 acts on the intermediary link 10 through the agency of the springs 7 and 26 described hereinabove so as to modify the adjustment obtained.

The embodiment illustrated in Fig. 3 differs from that of Fig. 2 merely through the replacement of the piston 6 by a diaphragm or membrane 6' made of rubberised canvas for instance, that is mounted and that acts in the same manner as the piston 2. The operation of the arrangement illustrated in Figs. 2 and 3 is similar to that disclosed with reference to Fig. 1 and it is not necessary to describe it any further; it should be merely pointed out that its operation is perfectly reliable.

What I claim is:

1. In a semi-automatic control system for the ignition timing mechanism in internal combustion engines provided with a carburettor including a throttle valve controlled by an accelerator pedal, the combination of a shiftable member submitted to the suction prevailing in the vicinity of the throttle valve, a link operatively connected with said member and controlling the timing mechanism, a correcting lever pivotally secured through one end to a stationary point and operatively engaging, at a point of its length, the link connected with the first member, a compensating lever, a floating connection between said compensating lever and the free end of the correcting lever and means controlled by the accelerator pedal and adapted to act on the correcting lever, and therethrough on said link, in the direction corresponding to advanced ignition when the throttle valve opens between a predetermined position and maximum opening.

2. In a semi-automatic control system for the ignition timing mechanism in internal combustion engines provided with a carburettor including a throttle valve controlled by an accelerator pedal, the combination of a shiftable member submitted to the suction prevailing in the vicinity of the throttle valve, a link operatively connected with said member and controlling the timing mechanism, a correcting lever pivotally secured through one end to a stationary point and operatively engaging, under floating conditions, at a point of its length, the link connected with the first member, a compensating lever, a floating connection between said compensating lever and the free end of the correcting lever and means controlled by the accelerator pedal and adapted to act on the correcting lever, and therethrough on said link, in the direction corresponding to advanced ignition when the throttle valve opens between a predetermined position and maximum opening.

3. In a semi-automatic control system for the ignition timing mechanism in internal combustion engines provided with a carburettor including a throttle valve controlled by an accelerator pedal, the combination of a shiftable member submitted to the suction prevailing in the vicinity of the throttle valve, a correcting lever pivotally secured through one end to a stationary point, a link operatively connected with said above mentioned member and floatingly secured to a point of the correcting lever, a connecting rod operatively connecting said link with the timing mechanism, a lever controlled by the accelerator, a compensating spring mounted between the correcting lever and a stationary point, an acceleration spring mounted between a point

of last mentioned accelerator-controlling lever and the correcting lever, and acting in antagonism with said compensating spring on the correcting lever and therethrough on the link floatingly secured thereto.

4. In combination with a mechanism for timing the ignition in internal combustion engines provided with a carburettor including a throttle valve controlled by an accelerator pedal, the provision of a member submitted to the suction prevailing in the vicinity of the throttle valve, a link operatively connecting said member with the timing mechanism, a correcting lever pivotally secured through one end to a stationary point and provided with an opening at a point of its length in which opening the link is carried freely, a synchronizing spring mounted between the member submitted to suction and the correcting lever, an auxiliary compensating spring inserted between the link and the correcting lever and acting in antagonism with the first mentioned spring to provide a floating mounting of the link with reference to the correcting lever, a lever controlled by the accelerator, a compensating spring mounted between the correcting lever and a stationary point and an acceleration spring mounted between a point of the accelerator-controlled lever and the correcting lever and acting in antagonism with last mentioned compensating spring on the correcting lever and therethrough on the mechanism-controlling link.

5. In combination with a mechanism for timing the ignition in internal combustion engines provided with a carburettor including a throttle valve controlled by an accelerator pedal, the provision of a member submitted to the suction prevailing in the vicinity of the throttle valve, a stationary casing enclosing the member submitted to suction, a link operatively connecting said member with the timing mechanism, a correcting lever, a pivot in the casing revolvably carrying said correcting lever, a synchronizing spring mounted between the member submitted to suction and the correcting lever, an auxiliary compensating spring inserted between the link and the correcting lever and acting in antagonism with the first mentioned spring to provide a floating mounting of the link with reference to the correcting lever, a lever controlled by the accelerator, a compensating spring mounted between the correcting lever and a stationary point and an acceleration spring mounted between a point of the accelerator-controlled lever and the correcting lever and acting in antagonism with last mentioned compensating spring on the correcting lever and therethrough on the mechanism-controlling link.

6. In combination with a mechanism for timing the ignition in internal combustion engines provided with a carburettor including a throttle valve controlled by an accelerator pedal, the provision of a chamber including a diaphragm submitted to the suction prevailing in the vicinity of the throttle valve, a link operatively connecting said diaphragm with the timing mechanism, a correcting lever pivotally secured through one end to a stationary point provided with an opening at a point of its length in which opening the link is carried freely, a synchronizing spring mounted between the diaphragm submitted to suction and the correcting lever, an auxiliary compensating spring inserted between the link

and the correcting lever and acting in antagonism with the first mentioned spring to provide a floating mounting of the link with reference to the correcting lever, a lever controlled by the accelerator, a compensating spring mounted between the correcting lever and a stationary point and an acceleration spring mounted between a point of the accelerator-controlled lever and the correcting lever and acting in antagonism with last mentioned compensating spring on the correcting lever and therethrough on the mechanism-controlling link.

7. In an internal combustion engine, the combination of ignition means, a timing mechanism therefor, an input pipe, a throttle valve therein, a member submitted to the depression prevailing inside the input pipe in the close vicinity of the throttle valve, a mechanical linkage directly and operatively connecting the last-mentioned member with the timing mechanism, a stationary pivot, a lever pivotally secured thereto and adapted to yieldingly engage the last mentioned mechanical linkage, a compensating member, means controlling simultaneously the throttle valve and the compensating member and a floating connection between said compensating member and the pivoting lever and adapted to constrain the latter to act on the mechanical linkage in the direction corresponding to advanced ignition as soon as the control means for the throttle member have overcome the resistance of said last-mentioned floating connection.

8. In an internal combustion engine, the combination of ignition means, a timing mechanism therefor, an input pipe, a throttle valve therein, a member submitted to the depression prevailing inside the input pipe in the close vicinity of the throttle valve, a mechanical linkage directly and operatively connecting the last-mentioned member with the timing mechanism, a stationary pivot, a lever pivotally secured thereto, a floating connection between said lever and the mechanical linkage through which the pivoting movement of the lever is adapted to shift said linkage in at least one direction of operation, a compensating member, means controlling simultaneously the throttle valve and the compensating member and a floating connection between said compensating member and the pivoting lever and adapted to constrain the latter to act, through the first floating connection, on the mechanical linkage in the direction corresponding to advanced ignition as soon as the control means for the throttle member have overcome the resistance of said last-mentioned floating connection.

GAGLIO, OSWALD.
